UNITED STATES PATENT OFFICE

2,558,618

BOTTLE CARRIER

Samuel N. Lebold, Chicago, Ill., assignor to Morris Paper Mills, Chicago, Ill., a corporation of Illinois

Application January 8, 1948, Serial No. 1,236

5 Claims. (Cl. 229—52)

1

The subject of this invention is an improved article carrier or portable container, of the type commonly employed in transporting bottled beverages, which is fabricated from paper board stock. In particular, the invention pertains to a carrier of this type which is suspended for transportation by means of a separate, pre-formed handle of wire or other relatively rigid material, which handle is associated with the container portion of the carrier, in accordance with the invention, in a novel and improved manner.

The invention deals with paper board bottle carriers of the type illustrated and described in the patent to Arneson No. 2,345,565, of April 4, 1944. Carriers of this type are constructed from a one-piece paper board blank folded and creased to enable the same to be quickly erected without the use of adhesive to an erected, operative condition. In this condition the carrier has a triangular shape in cross section and is provided with a pair of spaced openings along the longitudinally extending apex thereof through which the supporting lugs of a bail-type handle are received to suspend the carrier and its contents.

It has been found that the aforesaid handle lugs are apt to exert a destructive wearing or tearing effect on the carrier, particularly upon re-use, by reason of the stress imposed by said lugs on the single thickness apex line along and under which they engage. This may become so pronounced as to result in failure following repeated re-use or rough treatment of the loaded carrier.

It is therefore a general object of the invention to provide an inexpensive paper board carrier for bottles or like articles of the foregoing type, characterized by inclined, convergent side walls or panels and a central apex at the junction thereof which is supportingly engaged by a handle member, which carrier embodies novel provisions for substantially reinforcing the same adjacent said apex, whereby to possess increased resistance to tearing stress imparted by the handle.

A more specific object is to provide a carrier construction of the foregoing type including reinforcing tabs cut from the side walls or panels of the carrier and bendably connected thereto in a fashion to permit their inward and upward folding into intersecting relation to said apex, thereby to present an additional thickness of material beneath the apex for engagement by the handle or handle lugs.

2

Yet another object is to provide a bottle or like carrier of the type described, including integral reinforcing elements foldable to operative reinforcing relation underlying the apex or meeting line of a pair of side panels of the carrier, which elements are adapted to be readily and quickly disposed in said operative position while the carrier is being erected and are provided with means to enable their frictional retention in said position until and while a separate handle member is engaged therewith.

The foregoing statements are indicative in a general way of the nature of the invention, but other and more specific objects will be apparent to those skilled in the art upon a full understanding of the construction and operation of the device.

Two embodiments of the invention are presented herein for purpose of exemplification, but it will be appreciated that the invention is susceptible of incorporation in other modified forms coming equally within the scope of the appended claims.

In the drawings,

25 Fig. 1 is a plan view illustrating a blank from which an article carrier in accordance with one embodiment of the present invention is constructed;

30 Fig. 2 is a plan view illustrating the blank of Fig. 1 following manipulation of certain parts thereof during the operation of erecting the carrier;

35 Fig. 3 is a view in side elevation, partially broken away and sectioned, illustrating the co-action of the relationship of the reinforced apex of the carrier, in the erected condition of the latter, with a separate, relatively rigid handle member;

40 Fig. 4 is a fragmentary view in vertical transverse section along a line generally corresponding to line 4—4 of Fig. 3;

45 Fig. 5 is a fragmentary view in vertical, longitudinal section on line 5—5 of Fig. 4;

Fig. 6 is a plan view illustrating a somewhat modified adaptation of the invention to a bottle carrier of greater capacity than that represented in Figs. 1 through 5;

Fig. 7 is a view generally similar to Fig. 2 showing the blank of Fig. 6 with portions in 50 folded position;

Fig. 8 is a view in side elevation, partially broken away and sectioned showing the operative relationship of the handle and the multiple ply reinforcing elements of the modified type carrier; and

Fig. 9 is a view in transverse section along line 9-9 of Fig. 8, further illustrating structural details of the carrier and handle, and their relationship.

Referring to Figs. 1 through 5, the reference numeral 10 generally designates a died out blank of inexpensive grade of flexible paper board or cardboard from which the present bottle carrier, which is of the general type shown in the above identified Arneson patent, is constructed. This blank is cut and creased to provide a pair of generally similar side panels 11, 11, flexibly conjoined to one another along a medial crease line 12, and provided with end panels 13. Said panels subdivided by the angular divergent creases 14 and by an extension 12' of medial crease 12 into generally triangular end-forming walls 15 and flexibly connected triangular tuck flaps or portions 16. In order to facilitate initial inward folding of the walls 15 and flaps 16 to their operative position, the blank is provided with small apertures 17 on said extensions 12' and immediately adjacent the creased margins 18 by which panels 13 are flexibly conjoined to the side walls 11.

Crease line 12 is also provided with handle receiving apertures 19 equally spaced inwardly from the creases 18, said apertures being adapted to receive a separate bail-type wire suspending handle such as is illustrated in Figs. 3, 4 and 5 and designated by the reference numeral 20. This handle carries in-turned lugs 21 adapted to engage beneath the apex at which side walls 11 meet, represented by the medial line 12.

Each of the side walls is appropriately slotted and creased to provide a set of flaps which are normally disposed in the plane of the side wall, in the condition of the carrier prior to use, and which are bendable downwardly and internally of the latter to subdivide the interior of the container portion of the carrier. In the case of one of the side walls, the set of flaps include the identical, spaced end flaps 22 flexibly conjoined to the wall along hinge lines 23, a pair of intermediate flaps 24 in the intervening space which are hinged to the side wall at 25 and adapted to be swung inwardly, so as to subdivide the internal volume of the carrier into three article receiving cells on a side of its central plane, and a third intermediate tongue 26 hinged to the carrier wall at 27.

The set of flaps on the other side wall is generally similar, but certain thereof are somewhat modified in shape and in other details; hence the corresponding parts will be indicated by similar reference numerals primed. Thus, the flaps 22' are of somewhat lesser length than flaps 22, for a purpose to be described. They are provided with crease lines 28 which parallel their hinge lines 23' and are located the same distance from said hinge lines as the distance the latter are spaced from medial crease 12. Holes 29 are provided on the fold lines 28 at locations having the same spacing as the apertures 19 from the marginal creases 18.

The object of the above provisions, it will be perceived, is to insure that when flaps 22' are folded upon hinge lines 23, the respective holes 29 and creases 28 will come into register with and overlie the apertures 19 and medial crease 12, and that the portions of flaps 22' on either side of fold line 28 will lie in superposed contact with the respective panels 11 on opposite sides of medial crease 12. Yet the shortened length of said flaps avoids their hindering the free swing-

ing of the mutually opposed flaps 22 about their respective hinge lines 23.

The flaps 24', 26' are identical to the elements 24 and 26 and identically related to the respective side wall from which they are cut. As illustrated and described in the aforesaid Arneson patent, when the flaps 22, 22', 24, 24', 26 and 26' are swung internally of the carrier interior, bottle-receiving apertures are exposed in the side walls 11 for the reception of the contents to be transported and the interior of the carrier is subdivided roughly into rows of article receiving spaces on either side of the apex 12. However, in the present invention the flaps 22' serve a further purpose, as will be described.

The blank of Fig. 1 is completed by the bottom-forming panel 30, flexibly conjoined by fold line 31 to the outer or bottom margin of one of the side walls, and by locking flaps 32 flexibly conjoined along line 33 to the opposite margin of the other side wall. These last named flaps carry locking ears 34 which are receivable in a slot 35 in the bottom 30 to hold the carton in the erected condition thereof, which is shown in Fig. 3.

In setting up the carrier the flaps 22' are first swung about their respective hinges 23' to overlying relation to medial crease 12. The inwardly directed lugs 21 of the separate wire handle 20 are then successively inserted in the respective openings afforded by the superposed or registering apertures 19, 29, as by bending the blank in the fashion illustrated and described in the Arneson patent. This locates said lugs in underlying relation to a double thickness of material at the medial line 12, so that upward tearing stress subsequently applied thereto when the carrier is completed, loaded and suspended by the handle is effectively resisted. End forming walls 15 and tuck flaps 16, of the end panels 13 are then folded inwardly around lines 12', 14 and 18 while the side walls 11 being brought toward one another about the medial line 12, so as to place the side walls in the upwardly convergent relationship shown in Fig. 4. The bottom locking flaps 32 are next engaged in slot 35 of bottom 30 to hold the carrier in a triangular sectional shape without the use of adhesive or any other fastening means.

The apex at 12 of the thus erected carrier is greatly reinforced by the infolded reinforcing flaps 22' for engagement by the handle lugs 21 and the frictional engagement of these flaps, on opposite sides of the line 23', with the respective side walls 11 effectively resists displacement when the carrier is not suspended. The remaining flaps 24, 24', 26, 26' are available as inwardly extending dividing elements for the carrier interior.

The embodiment of the invention illustrated in Figs. 6 through 9 possesses all of the advantages of the construction just described. It differs therefrom mainly in that a carrier of 12-bottle capacity is involved, rather than a six-bottle carrier. Accordingly for the purpose of simplicity, similar reference numerals have been employed to designate parts which are structurally or functionally the same as those appearing in Figs. 1 through 5.

It should be particularly noted that, in the embodiment in Figs. 6 through 9, the hinge lines 36 for the innermost pairs of reinforcing flaps 37, cut from the material of the side walls, are disposed at an angle to the medial crease line or apex 12 and that the intermediate flap fold lines 38 are also angled relative to said apex. The

purpose of this is to insure that the holes 39 in said fold lines fall into register with the apertures 19 on line 12. Such disposition is necessary in view of the fact that said apertures 19 are positioned more widely apart than the extreme limits of flaps 37; and this is in turn by reason of the greater capacity of the carrier and a somewhat different cutting of its side walls to receive bottles.

The manipulation of the blank for the augmented capacity carrier in setting up the same is identical with that involved in the form of Figs. 1 through 5, and the completed carrier is shown clearly in Figs. 8 and 9, particularly in the relation of the separate handle member 20 and its lugs 21 to the paper board body of the carrier.

I am aware that those skilled in the art will perceive the possibility of altering the structure shown and described in a manner to accomplish the purposes encompassed thereby and I therefore desire that the invention be construed no more limitedly than is reasonably consistent with the scope of the appended claims.

I claim:

1. A closed top type bottle carrier of flexible fibrous material comprising a container having upwardly exposed, upwardly extending side walls each provided with a set of bottle receiving holes and tabs cut from the material of and hingedly connected to said side walls, said tabs normally covering said bottle receiving holes and certain thereof being swingable inwardly and upwardly of the container and into engagement with the top of the container between said sets of holes, said tabs being of sufficient length to transversely overlie the center line of the container between said sets of holes when so positioned, said container top having handle accommodating holes located adjacent said center line in the zone of said inswung tabs, and a bail type handle receivable in said holes and including means underlying and upwardly engaging said tabs when the container is suspended from the handle.

2. An article carrier comprising a container portion having opposed, upwardly convergent wall panels connected to one another adjacent the apex of convergence thereof, and provided with spaced holes adjacent said apex, said panels being provided with cuts defining article receiving openings therein and tab elements integrally and bendably connected thereto and normally lying in said openings, said tab elements being foldable from their normal position inwardly of the container portion and upwardly toward said apex, said tab elements being of sufficient length from the line of fold to the free edge thereof and being so disposed as to transversely intersect said apex and lie adjacent said hole when folded, and a bail type handle having supporting elements disposed in said holes and underlying said tab elements in engagement with the latter when the container portion is suspended from said handle.

3. An article carrier comprising a container portion having opposed, upwardly convergent walls connected to one another adjacent the apex of convergence thereof, and provided with spaced

holes adjacent said apex, said walls being provided with cuts defining article receiving openings therein and tab elements integrally and bendably connected thereto and normally lying in said openings, said tab elements being foldable from their normal position inwardly of the container portion and upwardly toward said apex, said tab elements being of sufficient length from the line of fold to the free edge thereof and being so disposed as to transversely intersect said apex and lie adjacent said hole when so folded, and a bail type handle having supporting elements disposed in said holes and underlying said tab elements in engagement with the latter when the container portion is suspended from said handle, said tab elements being creased in register with said apex to permit folding therebeneath and having internal wedging engagement with said walls on opposite sides of the apex to retain the tab elements in place when so folded.

4. An article carrier comprising a container portion having opposed, upwardly convergent wall panels connected to one another adjacent the apex of convergence thereof and provided with spaced holes adjacent said apex, said panels being provided with cuts defining article receiving openings therein and tab elements integrally and bendably connected thereto and normally lying in said openings, said tab elements being foldable from their normal position inwardly of the container portion and upwardly toward said apex, said tab elements being of sufficient length from the line of fold to the free edge thereof and being so disposed as to transversely intersect said apex and lie adjacent said hole when folded, and a bail-type handle having supporting elements disposed in said holes and underlying said tab elements in engagement with the latter when the container portion is suspended from said handle.

5. A bottle carrier of flexible fibrous material comprising a container having upwardly convergent side walls each provided with a set of bottle receiving openings and tabs hingedly connected to said side walls, said tabs normally lying in certain of said openings and being swingable on the hinges thereof inwardly and toward the apex of convergence of said walls into engagement with the latter, and being of sufficient length to transversely overlie the apex when so positioned, said apex having longitudinally spaced handle accommodating holes therein located adjacent said tabs, said handle accommodating holes being adapted for the reception of a bail type handle to position the latter for upward engagement with said tabs when the container is suspended from the handle.
